UNITED STATES PATENT OFFICE.

JOHN B. HEVERLING, OF GREENVILLE, OHIO.

IMPROVEMENT IN CAR-COUPLEINGS.

Specification forming part of Letters Patent No. 121,051, dated November 21, 1871.

To all whom it may concern:

Be it known that I, JOHN B. HEVERLING, of Greenville, Darke county, Ohio, have invented certain Improvements in the Method of Coupling Railroad Cars, of which the following is a specification:

My invention, being self-acting, is designed to avoid the necessity of entering between the cars to couple them, as is now done to the great danger of life and limb. Its operation is as follows, the several parts being set forth in the accompanying drawing, viz.:

Figure 1 is a vertical section, showing A, the hook, with its points D and B and elongated slot *d*, through which a pin passes; D, point which forces out the slide C. C is a horizontal slide, of iron or wood, which is forced out on raising the hook, which it supports until struck by the link attached to the opposite car. Fig. 2 represents the position after the cars are coupled.

The hook B being raised and resting on the sliding bar C, the cars are coupled by gently moving them together; the coupling-link attached to

one car enters the mouth of the opposite coupler, which is made large and flanging for this purpose, and, striking the slide C, throws it back, the hook B falling into its place, completing the operation.

The cars are uncoupled by lifting the hook B, which may be done from the top of the car by a small chain or rope fastened to a small ring in the top of the draw-bar and at the top of the car.

The material used for its manufacture should be cast or wrought iron, though wood might also be used.

I claim as my invention—

The combination of the hook A having the points B and D, and the shank slotted at *d*, with the slide C, for the purposes and in the manner above described.

JOHN B. HEVERLING.
